UNITED STATES PATENT OFFICE.

AUGUST E. W. JAHN, OF NEW YORK, N. Y., ASSIGNOR TO TROY LAUNDRY MACHINERY COMPANY, LTD., A CORPORATION OF NEW YORK.

CENTRIFUGAL EXTRACTOR.

1,193,697.

Specification of Letters Patent.

Patented Aug. 8, 1916.

Application filed August 4, 1914. Serial No. 854,933.

To all whom it may concern:

Be it known that I, AUGUST E. W. JAHN, a citizen of the United States, residing at New York, in the county of New York and 5 State of New York, have invented certain new and useful Improvements in Centrifugal Extractors, of which the following is a specification.

My invention relates to improvements in 10 centrifugal extractors and in particular to a guide for the rotary basket of such an extractor.

In centrifugal extractors such as are used 15 in laundries it is desirable and the common practice to have the rotary perforated basket in which the clothes are placed mounted upon a shaft or spindle which revolves at a very high rate of speed. The most usual and practicable construction requires that the 20 basket be mounted at or adjacent to the end of the spindle and a considerable distance from the bearing in which the spindle revolves, but this arrangement has resulted in violent oscillations and vibrations of the 25 swiftly rotating basket relatively to its normal axis of rotation especially when the basket is carelessly or improperly loaded, thereby imposing great strains upon the spindle and its bearings and causing great 30 danger of injury to other parts of the machine.

It is therefore the principal object of my 35 invention to provide a lateral support or guide for the rotary basket of a centrifugal extractor.

A further object is to provide a guide or bearing for the extractor which will have the least possible tendency to reduce the speed of the rotating basket.

40 Still another object is to provide a guide or bearing for the basket which will possess sufficient resiliency to permit limited vibrations of the basket, while at the same time dampening such vibrations and preventing 45 such violent oscillations as are liable to cause injury to the different parts of the machine.

These and other objects will be more particularly set forth and made apparent in the following specification, taken in connection with the accompanying drawings, in which I have illustrated several different forms of 50 my invention.

55 Referring to the drawings—Figure 1 shows a perspective view of a centrifugal extractor. Fig. 2 shows a vertical central

section through a portion of the extractor shown in Fig. 1 showing the application of my improved bearing or guide attachment. Fig. 3 is a horizontal sectional view taken on the irregular line 3, 3 of Fig. 2. Fig. 4 6 is a view similar to that of Fig. 2, showing a different form of my invention. Fig. 5 is a sectional view taken on the line 5, 5 of Fig. 4. Fig. 6 is a perspective view of a portion of the upper supporting ring shown 65 in Figs. 4 and 5. Fig. 7 is a perspective view of a portion of the lower supporting ring shown in Figs. 4 and 5. Fig. 8 is a vertical 70 sectional view similar to that of Fig. 2, but showing a third form of my invention. Fig. 9 shows a section view taken on the line 9, 9 of Fig. 8. Fig. 10 shows a vertical section through the upper retaining ring of Fig. 8 showing a ball bearing in elevation. Fig. 11 is a perspective view showing a portion 75 of the upper retaining ring of the form shown in Figs. 8 and 9. Fig. 12 shows a vertical sectional view similar to that of Fig. 2, illustrating a fourth form of my invention. Fig. 13 shows a sectional view 80 taken on the line 13 of Fig. 12. Fig. 14 shows a vertical section through one of the rollers illustrated in Figs. 12 and 13; and Fig. 15 shows a perspective view of a bracket member in which the rollers shown in Figs. 85 12, 13 and 14 are mounted.

Like numerals refer to like parts and elements throughout the drawings.

Referring to Fig. 1, the frame of the centrifugal extractor is shown as comprising a 90 shell 10, a standard 11, and a bearing base 12, the latter part being adapted to be secured to a floor or supporting base by any suitable means. Mounted in a suitable step bearing in the base 12 is a rotary spindle 13 95 which extends upwardly into the shell 10 where it is secured to a basket flange 14 upon which the rotary perforated basket 15 is concentrically mounted, as shown, for instance, in Fig. 2. Adjacent its lower end 100 the spindle 13 carries a spindle pulley 16, which is adapted to be connected by a belt to any suitable source of power. In the form of centrifugal extractor illustrated in the drawings, a supporting bracket 17 extends 105 upwardly at one side of the machine and carries a countershaft having the drive wheel 18 fixed thereon. The drive wheel 18 is adapted to be connected by a belt to the spindle pulley 16 by a belt passing around 110

the loose pulley 19. Mounted on the counter-shaft adjacent the drive wheel 18 are a fixed pulley 20 and loose pulley 21 adapted to be connected by a belt to a suitable source of power. When it is desired to put the machine in operation the belt from the source of power may be transferred from the loose pulley 21 to the fixed pulley 20 by means of the reciprocating rod 22 having the hooks 23 depending therefrom. When it is desired to stop the machine the belt is transferred back on to the loose pulley and a brake may be operated by means of the front pedal 24 to quickly reduce the velocity of the rotating spindle and basket. The parts above described form no part of my present invention and are shown merely as a basis for illustrating the different forms of my improved guide or bearing member for the rotary basket.

Referring to Figs. 2 and 3, a bracket member 25, having the depending flange 25^a and the radially extending flange 25^b, is shown secured by any suitable means to the inner wall of the shell 10. The inwardly extending flange 25^b serves as a support for a lower supporting ring 26, which is mounted in fixed position concentrically with the basket 15. The lower supporting ring 26 has a lower offset and inwardly extending flange 26^a and has secured thereto by any suitable means the upper supporting ring or cover plate 27. The lower offset flange of the supporting ring 26 and the upper cover plate or supporting ring 27 form a cage for the ball bearings 28, which are adapted to loosely fit therebetween. A bearing ring 29 is suitably mounted on the basket 15 inwardly of the ball bearings 28 and said balls are adapted to be maintained substantially in contact with said bearing ring by means of an outer retaining ring 30 preferably formed of steel or other hard material. Between the steel ring 30 and the vertical web of the supporting ring 26 is a layer 31 of rubber or the like which gives a limited resiliency to the construction and permits the basket 15, together with the retaining ring 30, to move bodily in a direction transversely to the axis of rotation of the basket, thereby permitting limited vibrations of the rotating parts, such as commonly occur in all elements rotating at high speed, at the same time preventing violent oscillations or vibrations of the basket and spindle, such as are liable to cause injury to the parts of the machine. It will be apparent that the parts which form the cage for the ball bearings may be readily disassembled so that the balls or other parts may be readily replaced in case they become worn or broken.

Referring to the form of my invention illustrated in Figs. 4 to 7, inclusive, the upper supporting ring 35 has a depending

flange 35^a which is adapted to be secured by any suitable means to the wall of the shell 10 and which also serves as a support for the upwardly extending flange of the lower supporting ring 36. Suitable ball bearings 37 are mounted between the upper and lower supporting rings which form a cage therefor and said bearings are adapted to coact with the bearing ring 29^a secured to the wall of the rotary basket as in the previously described form of my invention. An outer retaining ring 38 coacts with the balls 37 and is adapted to retain the same substantially in contact with the bearing ring 29^a. For the purpose of providing a resiliency which will permit a limited vibration of the rotating basket, I make use of a plurality of leaf springs 39 of the form shown in Fig. 5, these springs being adapted to be secured at the points 39^a intermediate their ends to the outer surface of the retaining ring 38. The extremities of said springs 39 are curved inwardly as shown in Fig. 5 and are adapted to contact with and slide upon the inner surface of the shell 10. It will be apparent that in case a limited vibration of the rotary basket occurs the springs 39 will permit a limited lateral movement of the retaining ring 36, while at the same time maintaining a substantially fixed guide for the rotary basket and thereby preventing violent vibrations or oscillations thereof.

In the preceding forms of my invention I have shown a plurality of ball bearings arranged in close relation to each other extending completely around the rotary basket.

In Figs. 8 to 11, inclusive, I have shown another form of my invention in which the ball bearings are spaced apart about the periphery of the basket. In this form the lower retaining ring 40 has an upwardly extending flange 40^a secured to the wall of the shell and the upper supporting ring or cover plate 41 has a depending flange 41^a adapted to be secured to the inner side of the flange 40^a. An outer retaining ring 42 is adapted to loosely fit between the supporting rings 40 and 41 and retain the ball bearings 43 substantially in contact with the bearing ring 29^b carried by the perforated basket. In order to provide means for spacing the ball bearings apart around the periphery of the basket, I make use of an upper retaining and spacing ring 44, which is provided with the offset looped portions 44^a having the vertically extending side walls 44^b, which maintain the ball bearings 43 in proper relative angular position. It will be understood that this upper retaining ring 44 is loosely mounted relatively to the upper supporting ring 41 so that it may move bodily, together with the outer retaining ring 42, in a direction transversely to the axis of rotation of the basket. In order to

provide a resiliency which will permit a limited vibration of the rotating parts, I make use, as in the second form of construction, of leaf springs 45 which are secured to the outer surface of the outer retaining ring 42 in radial alinement with each of the ball bearings 43. It will be apparent that in this form of construction, as in the other forms, the inner extremities of the upper 10 and lower supporting rings are spaced slightly from the bearing ring carried by the rotary basket so that a limited lateral vibration of said basket is permissible, but in each case the resilient mounting of the outer retaining ring, while permitting such limited vibration, operates to prevent the violent oscillations.

Referring to Figs. 12 to 15, inclusive, I have shown another form of my invention 20 in which the bearings are spaced apart around the periphery of the rotary basket. In this form of my invention individual bracket or supporting members 50 are provided for each bearing or roller. These 25 brackets have vertically extending webs adapted to be secured to the shell of the extractor and have inwardly extending parts 50^a which form supports for the rollers 51 of the forms shown particularly in Fig. 30 14. These rollers 51 have parallel end faces and a convex outer surface which is adapted to coact with the bearing ring 29^c carried by the rotary basket. The parts 50^a of the bracket members 50 are provided with vertically alining apertures or slots 52 which serve as bearings or guides for pins 53 upon which the rollers 51 are mounted. The pins 53 are rigidly connected to the rollers 51 and are movable with respect to the parts 40 50^a in which they are mounted, it being apparent that the slots or apertures 52 are elongated radially from the axis of rotation of the basket. An outer retaining ring 54 contacts with the rollers 51 and serves to 45 maintain them substantially in contact with the bearing ring 29^c and springs 55 of the form described in connection with the second and third forms of my invention are secured to the outer surface of the supporting ring 50 54 in radial alinement with each of the rollers 51, thus providing the resiliency as set forth in connection with the previous forms of my invention. It will be apparent that when the rotating parts experience a 55 limited vibration the rollers and outer retaining ring will move bodily, the pins 53 sliding in the slots or apertures 52.

I have above described several different forms of my invention, each of which is 60 adapted to prevent violent oscillations or vibrations of the basket and other rotating parts of a centrifugal extractor without materially reducing the speed of such parts while at the same time permitting a limited 65 lateral movement of the basket owing to small

vibrations thereof as it rotates at high speed. In case influences arise which tend to produce vibrations and oscillations, the resiliently mounted retaining ring will operate to speedily dampen such vibrations and 70 restore the machine to normal smooth running conditions without furnishing a resistance so rigid as to cause breakage. It will also be apparent that in each form of my invention the parts may be readily dis- 75 assembled to permit repairs or replacements and it will also be obvious that my invention may be readily applied to substantially any form of centrifugal extractor without material alteration of the same.

While I have illustrated several particular forms of my invention in connection with a particular form of centrifugal extractor, it will be evident that my improved guide for bearing for the rotary basket of 85 an extractor may be applied to various different forms of extractors and may itself partake of various different forms of construction without departing from the spirit of my invention as defined by the appended 90 claims.

I claim:

1. The combination in a centrifugal extractor of a supporting frame, a shell carried by said frame, a spindle, a basket with- 95 in said shell and concentrically mounted on said spindle, a bearing for said spindle carried by said frame, and an antifriction bearing for said basket carried by said shell.
2. In a centrifugal extractor, a frame, a 100 shell carried by said frame, a spindle rotatably mounted in said frame, a basket concentrically located within said shell and mounted on said spindle, and a ball bearing guide for said basket interposed be- 105 tween the same and said shell.
3. In a centrifugal extractor, a frame, a shell carried by said frame, a spindle rotatably mounted in said frame, a basket concentrically located within said shell and 110 mounted on said spindle, a bearing ring carried by said basket, and antifriction bearings carried by said shell to coact with said bearing ring.
4. In a centrifugal extractor, a frame, a 115 shell carried by said frame, a spindle rotatably mounted in said frame, a basket concentrically located in said shell and mounted on said spindle, a bearing ring carried by said basket, to permit a limited vibration of 120 said basket.
5. In a centrifugal extractor, a frame, a shell carried by said frame, a spindle rotatably mounted in said frame, a basket concentrically located within said shell and 125 mounted on said spindle, a bearing ring carried by said basket, a cage carried by said shell, and antifriction bearings carried in said cage to coact with said bearing ring.
6. In a centrifugal extractor, a frame, a 130

- shell carried by said frame, a spindle rotatably mounted in said frame, a basket concentrically surrounded by said shell and mounted on said spindle, a bearing ring carried by said basket, a cage carried by said shell, antifriction bearings carried in said cage, and resiliently mounted means to maintain said bearings in contact with said bearing ring.
- 5 7. In a centrifugal extractor, a frame comprising a shell, a spindle rotatably mounted in said frame, a basket mounted on said spindle within said shell, a bracket member carried by said shell, and antifriction bearings carried by said bracket member to coact with said basket.
- 10 8. In a centrifugal extractor, a frame comprising a shell, a spindle rotatably mounted in said frame, a basket mounted on said spindle within said shell, upper and lower supporting members carried by said shell, ball bearings mounted between said supporting members to coact with said
- 15 basket, an outer retaining member for said ball bearings mounted between said supporting members, and resilient means between said retaining member and said shell.
9. In a centrifugal extractor, a frame comprising a shell, a spindle rotatably mounted in said frame, a basket mounted on said spindle within said shell, upper and lower supporting members carried by said shell, ball bearings mounted between said supporting members to coact with said basket, means to space said ball bearings apart about the periphery of said shell, an outer retaining member for said ball bearings mounted between said supporting members, and resilient means between said retaining member and said shell.
- 20 40 In testimony whereof, I have subscribed my name.

AUGUST E. W. JAHN.
